United States Patent Office.

JOHN J. KIMBALL, OF NAPERVILLE, ILLINOIS.

Letters Patent No. 97,931, dated December 14, 1869.

IMPROVED WASHING-MACHINE.

The Schedule referred to in these Letters Patent and making part of the same.

To all whom it may concern:

Be it known that I, JOHN J. KIMBALL, of Naperville, in the county of Du Page, and State of Illinois, have invented a new and improved Washing-Machine; and I do hereby declare that the following is a full, clear, and exact description thereof, which will enable others skilled in the art to make and use the same, reference being had to the accompanying drawings, forming part of this specification.

This invention relates to improvements in washing-machines, and consists in an improved arrangement of operating-mechanism for revolving a vertically-suspended shaft, with a crank at the top, and carrying within the tube a corrugated or roughened rubber, for action on the clothes.

Figure 1 is a sectional elevation of my improved machine, and

Figure 2 is a horizontal section in the line *xx*.

Similar letters of reference indicate corresponding parts.

A is the vertical shaft, suspended from the top of the tub, and carrying the rubber B, by which the action is produced on the clothes.

This shaft has a crank at the top, the pin C of which is oval in form, and takes into a correspondingly-shaped groove or slot, D, in the end of an oscillating block, E, mounted on a horizontal axis, F, and arranged in any suitable way for the attachment of a working-lever, G,

The lever G, being vibrated, will move the wrist-pin back and forth, and the momentum of the crank-shaft will carry the crank-pin past the dead-points, whereby a rotary-motion will be imparted to the shaft and the rubber. But, as the momentum will sometimes be overcome by the friction on the rubber, I have provided, in addition to this arrangement, a sectional friction-disk, H, on the shaft, and a pair of curved friction-bars, I I', on projecting arms, K, of the block E.

These bars are attached to the arms K by screws L, so as to be adjusted toward or from the friction-disk on which they are designed to act, so that one bar will drive it one way, and the other, the other way; and the disk is so arranged on the shaft, relatively to the crank, that, at the moment the latter arrives at the "dead-point," the disk will be engaged with the bar I or I', to be carried past the said "dead-point."

The rubber B consists of a large block, of wood or other suitable substance, corrugated or grooved on the bottom, and is designed to be revolved above the clothes, so that its weight will be supported by them; and to accomplish this, it is fitted to the shaft so as to slide up and down thereon, and a pin or spline, M, is fitted to the shaft, to work in slots or grooves, N, in the wall of the hole through it.

By this arrangement, an equal and uniform action will be produced on the clothes, no matter what quantity the tub may contain.

Having thus described my invention, I claim as new, and desire to secure by Letters Patent—

1. The combination of the slotted vibrating block E, crank provided with wrist *c*, curved friction-bars I and I', and sectional frictional disk H, all constructed and arranged as shown and described, whereby either a uniform rotary or an intermittent rotary motion may be imparted to the rubber.

2. The washing-machine consisting of the several parts, all constructed, arranged, and operating as shown and described.

JOHN J. KIMBALL.
